(57) **CLAIM**

The ornamental design for a intestinal gas removal and conditioning device as shown.

DESCRIPTION

FIG. 1 is a top perspective view of the intestinal gas removal and conditioning device;

FIG. 2 is a bottom perspective view of the intestinal gas removal and conditioning device;

FIG. 3 is a side view of the intestinal gas removal and conditioning device;

FIG. 4 is a top view of the intestinal gas removal and conditioning device;

FIG. 5 is a side cross sectional view of the intestinal gas removal and conditioning device; and,

FIG. 6 is a bottom view of the intestinal gas removal and conditioning device.
